UNITED STATES PATENT OFFICE.

ROY N. STEWART, OF DORCHESTER, MASSACHUSETTS.

PUMP.

1,209,065.

Specification of Letters Patent.

Patented Dec. 19, 1916.

Application filed March 22, 1913. Serial No. 756,090.

To all whom it may concern:

Be it known that I, ROY N. STEWART, a citizen of the United States, residing at Dorchester, county of Suffolk, Commonwealth of Massachusetts, have invented certain new and useful Improvements in Pumps, of which the following is a specification.

This invention relates to pumps and particularly to a pump for variable water levels. 10 In pumps of this class, which are particularly designed for irrigating purposes, it is necessary to have the same operative and effective at a variety of levels in the source of supply. The condition of the usual supply varies widely and much practical difficulty has been experienced in finding a pump which will operate successfully under the most adverse conditions.

To this end I have devised my present invention in which I provide dual elements on a single shaft, one working auxiliary to the other and creating a working level for the main impeller when such does not naturally exist, in order that the supply may be had with certainty.

The construction and principle of my invention will be more fully disclosed in the specification which follows, and as illustrative of the same I have shown in the annexed drawings an embodiment which I have found well adapted for practical purposes.

Throughout specification and drawings like numerals of reference will indicate corresponding parts and in these drawings:

35 Figure 1 is a vertical central section through a pump in accordance with my invention, and Fig. 2 is a transverse section on the line 2—2 of Fig. 1.

I have indicated at 1 a base or foundation from which rises a casing 2 having a lateral flange 3 at its top which rests on supports 4 of any suitable construction. A vertical shaft 5 is journaled in a step bearing 6 at its lower end and in a thrust bearing 7 at its upper end. Power is applied to the vertical shaft 5 from a driven shaft 8 by a bevel gear 9 thereon in mesh with a similar gear 10 on said shaft 5. The rotation of the shaft 5 rotates a bladed impeller 11, mounted within a guide 12 and fastened on the lower end of said shaft near the bottom of the casing. A pair of gate valves 13 are hinged on opposite sides of the casing and control passages 14 between the walls of the casing and the impeller. The upper bladed impeller 15 on shaft 5 is of larger diameter

than the lower impeller 11 and its guide 16 is secured to the casing.

The operation is as follows: The shaft 5 is rotated through the gears 9 and 10 and 60 imparts rotation to the impeller blades 11 and 15. Should the water level in the casing be sufficiently high to provide an effective working area for the impeller 15, it will operate to lift the water from the casing. 65 In this event, the gates 13 open freely, but when the water level is so low as not to fill the water chamber between the two impellers, the valves will remain closed until the auxiliary impeller 11 has forced the 70 water through the passages 14 into the chamber above it. This new water level thus created offers an effective working area for the impeller 15 to become effective and raise the column for the delivery. This action is 75 entirely automatic and in a practical way overcomes the difficulties incident to a variable level.

Various modifications in the construction and form of my invention, coming within its 80 spirit and scope, may obviously be resorted to if found within the limits of the appended claims.

What I, therefore, claim and desire to secure by Letters Patent is:

1. In a variable level pump, a casing having a chamber, a shaft in said casing, a main impeller on said shaft in effective working relation to said chamber, auxiliary means to initially fill said chamber including an element rotatably but not longitudinally movable upon said shaft, and a valve associated with said auxiliary means and automatically becoming effective to permit said auxiliary means to create a new fluid 95 level in said chamber whenever the effective working area therein is insufficient for the needs of the main impeller.

2. In a variable level pump, a casing having a chamber, a shaft in said casing, a main 100 impeller on said shaft in effective working relation to said chamber, an auxiliary impeller rotatably but not longitudinally movable upon said shaft and adapted to initially fill said chamber, and means associated 105 with said auxiliary impeller and automatically becoming effective to permit said impeller to create a new fluid level in said chamber whenever the effective working area therein is insufficient for the needs of 110 the main impeller.

3. In a pump of the class described, a

shaft, a main impeller thereon, a casing in which said shaft is mounted, said casing having a chamber in effective working relation to said impeller, an auxiliary impeller 5 on said shaft, and gate valves coöperating with said auxiliary impeller to initially fill said chamber.

4. In a variable level pump of the class described, a casing having a liquid chamber, 10 a shaft in said casing, a pair of spaced impellers on said shaft, and means coöperating with one of said impellers to initially fill said chamber and automatically becoming effective to create a new fluid level when the 15 effective working area in the chamber is insufficient for the needs of the main impeller.

5. In a variable level pump, a casing, a shaft rotatable therein, a main impeller on said shaft, an auxiliary impeller on said 20 shaft defining with said main impeller and the casing an intermediate chamber arranged in effective working relation to the main impeller, and means coöperating with said auxiliary impeller to initially fill said 25 chamber and automatically becoming effective to create a new fluid level whenever the effective working area in said chamber is insufficient for the needs of the main impeller.

30 6. In a variable level pump, a casing, a shaft rotatable therein, a main impeller on said shaft, an auxiliary impeller on said shaft defining with said main impeller and the casing an intermediate chamber arranged in effective working relation to the 35 main impeller, and gate valves coöperating with said auxiliary impeller to initially fill said chamber and automatically becoming effective to create a new fluid level whenever 40 the effective working area in said chamber

is insufficient for the needs of the main impeller.

7. In a variable level pump, a casing, a shaft rotatable therein, a pair of spaced members in said casing having openings for 45 the passage of a fluid and defining an intermediate chamber, a pair of impellers mounted on said shaft in effective relation to the fluid openings through said members, one of said members having an auxiliary fluid 50 opening and a valve controlling said opening and coöperating with the impeller associated with said member to initially fill said chamber and said valve automatically becoming effective to permit said impeller to 55 create a new fluid level in said chamber whenever the effective working area therein is insufficient for the needs of the other impeller.

8. In a variable level pump, a casing, a 60 shaft rotatable therein, a pair of spaced members in said casing having openings for the passage of a fluid and defining an intermediate chamber, a pair of impellers mounted on said shaft in effective relation to the 56 fluid openings through said members, and means coöperating with one of said impellers to initially fill said chamber and automatically becoming effective to permit said impeller to create a new fluid level in 70 said chamber whenever the effective working area therein is insufficient for the needs of the other impeller.

In testimony whereof I affix my signature in presence of two witnesses.

ROY N. STEWART.
